UNITED STATES PATENT OFFICE.

SILAS L. MEEK, OF ALMA CENTER, WISCONSIN.

DRAFT-EQUALIZER.

1,036,135.

Specification of Letters Patent. Patented Aug. 20, 1912.

Application filed November 28, 1911. Serial No. 662,890.

To all whom it may concern:

Be it known that I, SILAS L. MEEK, citizen of the United States, residing at Alma Center, in the county of Jackson and State 5 of Wisconsin, have invented certain new and useful Improvements in Draft-Equalizers, of which the following is a specification.

This invention relates to draft equalizers 10 and is particularly adapted for use on wagons, trucks and the like, and aims to prevent swinging of the vehicle tongue when the forward wheels pass over obstructions in the road and at the same time to equalize the 15 draft between the animals when such interference is met.

A further aim is to equally apportion the load between the two animals should either one lag behind or keep in advance of the 20 other on the initial pull or during subsequent travel.

A still further object is to provide a simple, durable and efficient draft equalizer, capable of being manufactured at a relatively 25 low cost and so constructed that it may be readily attached to vehicles and the like in present service without altering the vehicle, thus tending to make more general the use of this class of devices.

30 Further objects and advantages will appear in the following description, it being understood that various changes in form, proportions and minor details of construction may be resorted to within the scope of 35 the appended claims.

For a full understanding of the invention and the merits thereof, reference is to be had to the following description and accompanying drawing, in which:

40 Figure 1 is a plan view of the device attached to a wagon; Fig. 2 is an elevation of the same; Fig. 3 is a vertical cross section on the line 3—3 of Fig. 1.

Corresponding and like parts are referred 45 to in the following description and indicated in all the views of the drawing by the same reference characters.

In order to clearly illustrate the operation of this improved draft equalizer it is shown 50 operatively attached to the fore part of a wagon, in which A designates the tongue B the axle, and C the wheels thereof. An evener or spacing bar 1 is disposed preferably above the tongue A and rests thereon, 55 being pierced near each end by eye bolts 2 which carry depending rings 3. A swing-

tree 4 is swiveled to a flexible member, preferably in the form of a chain 5, which latter is passed through the ring 3 and brought rearwardly to the axle B adjacent to the adjoining wheel where said chain is passed through a pulley block 6 which is secured to said axle, preferably by split collar 7 clamped about the axle by the bolts 8. After being passed through said pulley block, 60 the chain extends diagonally across to the other end of the spacing bar where it passes through the other ring 3 and thence to the adjacent swingtree. It will be noted that by this arrangement, the chains 5 cross beneath 65 the wagon tongue and each, after passing through the adjacent pulley and through the rings 3, is secured at each end to the swingtree adjacent thereto. In order to prevent the chains from rubbing against the tongue 70 A and nearby parts of the wagon construction, the eye bolts 2 are relatively long and are encircled by correspondingly thick washers 9 which reinforce and tend to prevent handling of said bolts. 75

During the travel of the wagon, if one of the wheels C strikes an obstruction D, there would, of course, be a resultant tendency to retard the movement of this wheel of the vehicle and also throw the tongue A to one 80 side and at the same time place unequal strain upon the draft animals. At this point, that is where the obstruction is encountered, the equalizer becomes operative 85 and prevents swinging of the tongue. The swingtree adjacent to the retarded wheel is allowed to advance and the opposite one to swing backward by virtue of the chains 5 acting through the pulleys 6, as shown by the dotted lines. A tendency to maintain 90 the swingtree adjacent to the retarded wheel is 95 allowed to advance and the opposite one to swing backward by virtue of the chains 5 acting through the pulleys 6, as shown by the dotted lines. A tendency to maintain the swingtree adjacent to the retarded wheel is 100 allowed to advance and the opposite one to swing backward by virtue of the chains 5 acting through the pulleys 6, as shown by the dotted lines. A tendency to maintain the swingtree adjacent to the retarded wheel is 105 allowed to advance and the opposite one to swing backward by virtue of the chains 5 acting through the pulleys 6, as shown by the dotted lines. A tendency to maintain the swingtree adjacent to the retarded wheel is 110 allowed to advance and the opposite one to swing backward by virtue of the chains 5 acting through the pulleys 6, as shown by the dotted lines.

It is desired to further direct attention to

the tendency to maintain equal draft on both animals, since if one lags behind or precedes the other, both will still continue to perform approximately the same amount 5 of work through the operation of the equalizing device, as will be seen by the dotted lines in Fig. 1. It will also be noted that all strain is withdrawn from the spacing bar 1 and other adjacent parts of the wagon, the 10 motive force being applied directly to the vehicle axle near the wheels so that a differential is established, since the greater power is always transmitted to the retarded wheel. If the spacing bar were bolted or otherwise 15 rigidly attached to the wagon tongue, this equalizing effect could not take place, and this point is one of the main features of the invention.

Having thus described the construction 20 and clearly set forth the merits of the device, it is hereby claimed:

1. The combination with a vehicle frame, of a draft equalizer including spaced swingletrees, a spacing bar resting loosely on the 25 vehicle tongue and adapted to maintain the swingletrees in spaced relation, flexible members slidably connected to said bar and each having one end thereof swiveled to each swingletree, the intermediate portion of each member being 30 slidably connected to the vehicle frame, and a spring connecting the bar with the wagon tongue and tending to maintain said bar in its normal position.

2. The combination with a vehicle frame, of a draft equalizer including spaced swingletrees, a spacing bar resting loosely on the 35 vehicle tongue and adapted to maintain the swingletrees in spaced relation, a spring connecting the bar with the tongue and tending to maintain the bar in its normal position, 40 depending rings swiveled to each end of the bar, pulley blocks secured to opposite ends of the vehicle axle, and flexible members, one passing through each block and having their opposite ends passed through the depending 45 rings and swiveled to the adjacent swingletree.

3. The combination with a vehicle frame, of a draft equalizer including spaced swingletrees, a spacing bar resting loosely on the 50 vehicle tongue, flexible members slidably connected to said bar and each having one end thereof swiveled to each swingletree, the intermediate portion of each member being 55 slidably connected to the vehicle frame, and a spring having one end thereof secured to the vehicle tongue and the other end secured to the spacing bar, said spring being adapted to maintain the flexible members under tension.

In testimony whereof I affix my signature in presence of two witnesses.

SILAS L. MEEK. [L. S.]
